UNITED STATES PATENT OFFICE.

ALVIN DUDFIELD, OF LIBERTY, AND GRANVILL P. MORRIS, OF KANSAS CITY,
MISSOURI.

VISIBLE STRIP SCREED AND GROUND.

Application filed February 26, 1927. Serial No. 171,257.

This invention relates to a visible strip screed and ground for use in applying wood or metal trim in fireproof construction work.

An important object of the invention is to provide a device of this character which is readily embedded in the finishing plaster work and which, in applied position, will be visible and readily accessible for the attachment of trim thereto.

10 A further object of the invention is to produce a readily constructed screed of such formation that it provides a socket for the reception of a wood block affording an attachment means and so houses the block that it cannot fall out should it be split in use.

These and other objects we attain by the construction shown in the accompanying drawings, wherein for the purpose of illustration is shown a preferred embodiment of 20 our invention and wherein:

Figure 1 is a plan view of a screed constructed in accordance with our invention;

Figure 2 is a vertical sectional view showing the same as applied in the wall;

25 Figure 3 is a sectional view showing the blank from which the trough and its flanges are formed, the dotted lines indicating the points at which the blank is to be bent.

Referring now more particularly to the 30 drawings, the numeral 10 generally designates a trough formed from sheet metal and having at its sides outstanding flanges 11, which lie wholly within parallel planes contacting the bottom wall 12 of the trough and

35 the upper ends of the side walls 13. These flanges are preferably made sinuous, being at present illustrated as having a single bend 14 formed therein intermediate their attached and unattached edges. In the

40 flange are formed openings 15 and 16 through which the wall plaster may pass to firmly lock the screed in position in the wall.

Within the trough is arranged a wood block 17, this block having its upper surface 45 substantially flush with the upper edges of the side walls and being retained in position in the trough by tabs 18 formed integrally with the body of the trough. In the present construction, the tabs 18 are formed by

50 cutting the material of the flanges 11 adjacent the point of attachment of the flange

to the side walls 13 of the trough in a semi-circle, the cord of which is the attached edge of the flange. The flap thus provided is then bent inwardly upon the upper surface 55 of the wood block 17 to retain the same in position. A screed of this character is applied to the wall with the bottom of the trough outwardly disposed. The wood block being firmly held within the trough and reinforced by the plastering thereabout will not fall out should it split or break when the trim is secured thereto. Under many circumstances, the tabs 18 are unnecessary, as the trough can be made to grip the 60 block with sufficient force to prevent loss thereof before the screed is inserted in the wall.

Since the construction hereinbefore set forth is capable of a certain range of change 70 and modification without materially departing from the spirit of the invention, we do not limit ourselves to such specific structure except as hereinafter claimed.

We claim:

1. A screed of the character described 75 comprising a trough having flanges extending outwardly from the upper ends of the side walls thereof, said flanges lying wholly between parallel planes contacting the bottom of the trough and the upper ends of the side walls thereof, said flanges being perforated, and a wood block within said trough.

2. A screed of the character described 80 comprising a trough having flanges extending outwardly from the upper ends of the side walls thereof, said flanges lying wholly between parallel planes contacting the bottom of the trough and the upper ends of the side walls thereof, said flanges being perforated, and a wood block within said trough, the trough having tabs engaging the wood block to maintain the same in position therein, said tabs being struck out 85 from the material of the flange to thereby provide certain of said openings.

In testimony whereof we hereunto affix our signatures.

ALVIN DUDFIELD.
GRANVILL P. MORRIS.
